(54) **STEAM, GENERATING**

(76) Inventor: **Job Carr**

Job Clegg of Springborough. No.

Letters Patent

The Schedule referred to in these Letters Patent and making part of the same containing a description in the words of the said Job Clegg himself of his improvement in the Steam Generator or Boiler.

It all to whom these presents shall come. Be it known that I Job Clegg of Springborough in the County of Lincoln and State of Ohio have invented a new and useful machine being an improvement in the common Steam Generator or boiler for generating a sufficient quantity of steam for propelling any kind of machinery, which invention is or may hereafter become of applicability without any danger of bursting, is, collecting, and that the following is a full description thereof. Make a vessel of Copper, Brass, or wood lined with copper and round in the following manner (of sufficient size to generate the quantity of steam required, always reserving allowance in the calculation for the size of the vessel and the case may be) make the bottom flat, sides straight or vertical and top circular, two feet or more if required, let a strong bar of iron be placed under the bottom with a hole in each end exactly over with the outside of the vessel, then another bar follow it with the ends extending through the first bar and well riveted with a good nail, have two or more strong bars, filled except each end of the receiver and let them extend round the vessel, with holes in each end through which the bars that go over the top of the ends are to pass before they are fastened at the bottom, so the further support of the vessel is made by strong bars through the same and let them pass through the ends and these bars on the ends and secure them well at each end. The number of these ends being to be regulated by the size of the receiver. The steam to be generated in this receiver by fire made of iron, copper, or any other metallic substance with a flange in the front end to make

These stoves. The size and number of the furnaces to be governed by the power required. Say for ordinary purposes, from two to two and a half feet in diameter with a vertical slope from 18 inches to two feet in more or less corresponding with the width of the furnaces necessary, namely the whole length of and coming through the front end of the receiver when the flange is to receive it. There is to be a door nearly the full size of the furnace for the purpose of putting in fuel with a small aperture in the lower edge to admit air. The bottom of the furnace at the front end to be grated and a false bottom attached slanting outward, for the purpose of catching and carrying out the fine coal and ashes near the back end of the furnace inserted a pipe of the same size to convey the smoke off to it, in line with the bottom of it about a foot with the top of the furnaces to the front of the receiver when adjusted to propelling 1000 lbs. There must be a partition between every two furnaces water tight extending from the top to the bottom (owing to the supply of water kept in the receiver) above the top of the furnaces to prevent the water from leaving the furnace in case of the boiler bursting or having a separate reservoir for each furnace connected similar to the Boiler now in use. The water to be supplied in the receiver and the steam taken from the same and applied to the engine on the small improved plan now in use.

What I claim is my own invention and not previously known in the above described machine is the combination of the receiver and furnace to improved Steam Generation and arrangement of the combined parts as above described and for the uses and purposes herein mentioned.
